UNITED STATES PATENT OFFICE.

GIBSON H. TURNER, OF ELECTRA, TEXAS.

WRENCH.

Application filed June 7, 1919, Serial No. 302,443. Renewed June 23, 1922. Serial No. 570,383.

To all whom it may concern:

Be it known that I, GIBSON H. TURNER, a citizen of the United States, residing at Electra, in the county of Wichita and State 5 of Texas, have invented new and useful Improvements in Wrenches, of which the following is a specification.

This invention relates to wrenches and particularly to that class of wrenches known 10 as "pipe wrenches."

An object of the invention is the provision of a wrench of this character which will automatically adjust itself to the diameter of a pipe, the construction being such as to 15 permit of its use upon pipes of various diameters.

Another object is the provision of a wrench which includes a sliding jaw held in position by a sliding pivot connection of 20 novel formation, so as to decrease the cost of manufacture and increase the width of the opening of the jaws.

Other objects and advantages of the invention will appear as the following description is read in connection with the accompanying drawings.

In the drawings:

Figure 1 is a side elevation of a wrench constructed in accordance with the present 30 invention and shown in closed position.

Figure 2 is a similar view with the jaws of the wrench open and parts broken away to more clearly show the sliding pivot connection of one of the jaws.

Referring in detail to the drawings, wherein like characters of reference denote corresponding parts, the wrench is shown as comprising a handle 10, which is provided with a substantially right angular extension 11. Pivotal secured to the outer end 40 of this extension is a jaw member 12, which may, if desired, be provided with an auxiliary gripping element 13, suitably secured thereto and having the usual serrated 45 toothed gripping face.

Pivottally and slidably secured to the extension 11, is a jaw 14, the outer end of the jaw being formed with an offset extension 15, which is also provided with a serrated or toothed gripping face. The inner 50 end of the jaw 14 is bifurcated to receive the extension 11, the arms 16 formed by the

bifurcation being connected by a pin 17. This pin passes through a slot 18 formed in the lower edge of the extension 11, the said slot being formed by notching this edge of the extension, as indicated at 19, a shoulder at each end of the notch acting as stops to limit the movement of the pin 17. This pin is held within the notch through the medium 55 of a plate 20, one end of which is secured to the extension near the outer end thereof by means of a screw 21, or other suitable fastening device. The opposite end of the plate is preferably provided with a right 60 angular extension 22, to provide an attaching ear for the passage of a screw 23, which serves to secure this end of the plate to the handle 11.

The jaw 12 is also bifurcated and straddles the extension 11, and has secured thereto through the medium of screws or analogous fastening devices 24, a strap or band 25. This strap or band passes around the 70 jaw 16 and acts as a guide.

It is preferred to provide the pin 17 with a roller 26, so as to reduce friction in the 75 operation of the wrench.

The invention is susceptible of various 80 changes in its form, proportions and minor details of construction and the right is herein reserved to make such changes as properly fall within the scope of the appended 85 claim.

Having described the invention, what is 90 claimed is:

A wrench comprising a substantially L shaped handle to provide an offset extension, a jaw member positively pivoted upon said extension, a second jaw member capable 95 of longitudinal sliding movement with respect to the first mentioned jaw member, a strap secured to the positively pivoted jaw member and engageable with the other jaw member to provide a guide, a pin carried by 100 the last mentioned jaw member, a notch formed in the under side of the offset extension of the handle, and a plate extending across the notch to provide a slot for the reception of the pin of the second jaw member to define a slotting pivotal connection with the handle.

In testimony whereof I affix my signature.

GIBSON H. TURNER.
